DESIGN FOR HANDLES OF SPOONS AND FORKS.

Design No. 11,212, dated May 27, 1879.

UNITED STATES PATENT OFFICE.

WILLIAM C. BEATTIE, OF TAUNTON, MASSACHUSETTS, ASSIGNOR TO REED
AND BARTON, OF SAME PLACE.

DESIGN FOR HANDLES OF SPOONS AND FORKS.

Specification forming part of Design No. **11,212**, dated May 27, 1879; application filed January 16, 1879.
[Term of patent 7 years.]

To all whom it may concern:

Be it known that I, WM. C. BEATTIE, of Taunton, in the county of Bristol and State of Massachusetts, have invented a new and useful Design for the Handles of Spoons, Forks, &c.; and I do hereby declare that the following is a full, clear, and exact description of the same.

My invention is in the nature of a new design for the handles of spoons, forks, &c., to which has been applied the name of "Orient."

The main feature consists in constructing the handle in the general form of a spear-head or dart having obtuse angles upon the sides and a blunted point.

Referring to the accompanying fac-simile, which illustrates a spoon, the handle is swelled near the extremity into the general form indicated, *a* representing the blunted point, and *b* the two obtuse angles on the sides, which give the general appearance of a blunted dart or spear-head. Between the widest portion of the spear-head and the shank or stem of the spoon is formed a small circularly swelled or enlarged part, *c*. The outer edges of the spear-

head, which converge toward the point or end of the handle, are straight lines, and the edges between the obtuse angles and the enlargement *c* are curved inwardly. The part *c* and the marginal parts of the handle are provided by stamping or engraving with suitable ornaments, the central parts of the handle being left plain.

Having thus described my invention, what I claim as new is—

1. The design herein described for the handle of a spoon or analogous implement, consisting of the general configuration of a spear-head or dart having a blunted point and obtuse angles upon the sides.

2. The handle made in the form of a spear-head, with obtuse-angled sides and a blunted point, and having an enlargement, *c*, between the same and the shank, as shown and described.

WILLIAM C. BEATTIE.
